BUSHING MOLD.

Application filed April 12, 1926. Serial No. 101,330.

Our invention relates to the class of molds, and is particularly, though not necessarily, intended for casting bushings, especially bushings for connecting rod bearings and the like.

The essential object of our invention is to provide a mold which may be made of cast iron or other suitable material, and the members of which may be readily and firmly assembled repeatedly for use, and easily and effectively parted or dismembered to release the molded product, without injury or damage either to the product or to the members of the mold.

To this end our invention consists in the novel mold which we shall hereinafter describe, by reference to the accompanying drawings, in which—

Fig. 1 is a top plan view of our mold.

Fig. 2 is a side elevation of the same.

Fig. 3 is a side elevation of the base member of the mold.

Fig. 4 are views in side, front, and end elevations respectively of the eye-bolts which are fitted to the body member.

1 is the base member of the mold, shaped to function at one end for the reception and support of the members which form the mold-space, and at the other end for the reception and support of the supply hopper, or, as it is known in the art, the gate member through which the molten metal is poured. The base member 1 on its upper face is formed as shown in Fig. 3 with raised 30 guide-boss 2 and with a recess 3. The upper face of said member 1 is also formed with a channel or groove 4 for the flow of the metal when pouring.

5 is the body member of the mold, constituting the outer wall of the mold space. It fits down over the guide boss 2 of base member 1 and separably rests upon said member. If, as indicated herein in Fig. 2, the bushing to be molded is to have an end flange, the lower end of the body member 5 is properly shouldered as shown at 6.

The body member 5 is formed with ears 7 into which are fitted the eye-bolts 8, for the reception of suitable chains, not shown, 50 for lowering the body member to and lifting it from its seat on the base member.

9 is the core member which constitutes the inner wall of the mold-space. It is composed of a plurality of sections, segmental in 55 cross-section and assembled in alternating

oppositely tapering relation, thus forming a readily collapsible annulus.

The core member 9 is separably seated in the recess 3 of the base member 1, and between said core member and the body member 5, is the mold-space 15, which at its bottom is in communication with the pouring groove 4 of the base member.

10 is the hopper member or "gate" into which the molten metal is poured. This member is made in two sections, as shown in Fig. 1, and it separably rests upon the base member in such position that it communicates with the underlying groove 4 in said base member.

The sections of the hopper member are held together by the clamp-yoke 11 and the associated wedge 12, said yoke resting on lugs 13 formed on the side faces of the hopper sections, as shown in Fig. 2. Pulling lugs 14 are also formed on the section sides.

The several members and parts of the mold being assembled as shown in Figs. 1 and 2, the molten metal is poured into the hopper or gate 10 and flows through said gate and through the groove 4 to the mold-space, in which and in the hopper it rises to the desired level. When the metal is cooled, the wedge 12 is knocked out, thereby releasing the clamp yoke 11, and by pulling force applied to the lugs 14 the sections of the hopper 10 are parted and removed. Then the hoisting chains are applied to the eye-bolts 8, and the body member 5, together with the core member 9 and the whole molded product are lifted away from the base member. Then the core member 9 is collapsed by driving apart its tapered sections; and, finally, that portion of the molded product foreign to the desired bushing is sawed off.

It will thus be seen that the mold is adapted for ready, convenient and effective assembling and dismembering, which are the objects for which it is designed.

We claim:—

1. A mold comprising a base member having in its upper surface a pouring channel; a body member separably supported upon said base member overlying the inner portion of said channel and constituting the outer wall of the mold space; a core member, separably supported upon the base member and constituting the inner wall of the mold space, said mold space at its base communicating with the pouring channel.

cating with the inner end of the pouring channel of the base member; and a hopper member separably supported upon said base member overlying and in communication 5 with the outer portion of the pouring channel thereof.

2. A mold comprising a base member having in its upper face a recess and a guide boss about said recess, and having also in its 10 upper surface a pouring channel; a body member separably supported upon said base member about said guide boss overlying the inner portion of said channel, and constituting the outer wall of the mold space; a collapsible core member separably supported within the recess of said base member and constituting the inner wall of the mold 15 space, said mold space at its base communicating with the inner end of the pouring channel of the base member; and a collapsible hopper member separably supported upon said base member overlying and in communication with the outer portion of the pouring channel thereof.
- 25 3. A mold comprising a base member having a pouring channel; a body member and a core member separably supported upon said base member and spaced apart to form the mold space between them, said space 30 communicating with the pouring channel in the base member; a sectional hopper

member separably supported upon the base member in communication with the pouring channel thereof; a detachable yoke for clamping the sections of the hopper member together; and a wedge for tightening said yoke.

4. A mold comprising a base member having in its upper face a recess and a guide boss about said recess, and having also a 40 pouring channel; a body member separably supported upon said base member about said guide boss and constituting the outer wall of the mold space; a core member composed of a plurality of longitudinally tapered sections assembled in alternating reversed fela- 45 tion, said core member being separably supported within the recess of the base member and constituting the inner wall of the mold space, said mold space communicating with the pouring channel of the base member; a hopper member composed of sections separably supported upon said base member in communication with the pouring channel thereof; and a detachable yoke and wedge 50 for holding the sections of the hopper member together.

In testimony whereof we have signed our names to this specification.

AUSTIN D. WILLIAMS.
FRANK B. GILLETT.
